ANGLE PLATE INDICATOR

Thomas Fitzpatrick, Syracuse, N. Y.

Application October 5, 1950, Serial No. 188,603

3 Claims. (Cl. 33—174)

This invention relates to a device for producing angular adjustments together with an indicator therefor and is more particularly concerned with a device of this type that is capable of producing extremely fine and accurate adjustments.

The primary object of the present invention is to provide a device which is capable of producing adjustments in degrees, minutes, and seconds so that extreme accuracy in adjustments can be accomplished.

Another object of the present invention is to provide a device such as described which is capable of use in a multiplicity of environments, the only change necessary being that of the manner in which the device is mounted.

A further object resides in the construction such as described wherein the mechanism is relatively simple and compact so as to occupy a minimum of space.

Other objects and advantages will appear as the description proceeds, and while the illustrated form is shown as applied to an angle plate, it is to be understood that the invention is not to be so limited, but is capable of application to a variety of members in which accurate angle adjustment is desired. For instance, the present invention is designed for use with spacer plates and is capable of use in jig boring, grinding, milling, drilling, layout engraving, and in fact in almost any location where it is desired to angularly adjust an element in degrees, minutes, and seconds.

Referring to the drawings,

Fig. 1 is a side elevation illustrating the present invention as applied to a plate the angle of which is to be adjusted.

Fig. 2 is a top plan view of my invention.

Fig. 3 is a bottom plan view.

Fig. 4 is a fragmentary sectional view taken on the line 4—4 of Fig. 1.

Fig. 5 is a sectional view taken on the line 5—5 of Fig. 1.

Fig. 6 is a vertical sectional view taken on the line 6—6 of Fig. 4, and

Fig. 7 is a horizontal sectional view taken on the line 7—7 of Fig. 4.

Referring more in detail to the drawings, it will be seen that the invention is shown as being applied to an adjustable angle plate which comprises a base 1, an adjustable angle plate 2, pivoted to upstanding lugs 3 and 4 secured to the base 1, the pivots being indicated at 5 and 6, and the angle plate 2 carries at opposite sides thereof arcuate arms 7 and 8 with the arm 7 being provided with rack teeth 9 along its outer edge.

Of course, the side face of the arm 7 is provided with suitable calibrations from zero to 90 indicating degrees, and the arms 7 and 8 are provided with arcuate slots such as indicated at 10 cooperating with a stud 11 and thumb nut 12 by means of which the arms 7 and 8 may be fixed in adjusted position.

Mounted on the base 1 is a bracket 13 attached to the base 1 in any suitable manner such as by means of the screws 14 and 15. This bracket extends vertically and is provided with spaced longitudinally extending shoulders 16 and 17, providing a groove therebetween forming a slideway and having plates 18 and 19 secured thereto by screws 20 and 21, which plates overhang a carriage 22 slidably mounted in the slideway.

As shown in Figs. 6 and 7, the carriage 22 is provided with a recess 23 at the rear end thereof to receive a coil spring 24 abutting a rear wall 25 of the bracket 13 and

2

normally urging the carriage 22 away from said rear wall and towards the arcuate arm 7.

Extending through one wall of the bracket 13 is a shaft 26 provided on one end with a cam 27 operating in a cam recess 28 in the carriage 22 and having at its other end an operating handle 29 by means of which the cam 27 may be rotated to retract the carriage against the force of the spring 24 and away from the arcuate arm 7. The contour of the cam recess is such that when the cam is rotated, the carriage 22 will not only be retracted, but will be held in its retracted position against the action of the spring 24.

The bracket 13 likewise carries a minute adjusting mechanism comprising a vertically extending shaft 30 carrying a knurled operating knob 31 at one end and journaled for rotation in spaced bearings 32 and 33 carried by the carriage and having secured thereto for rotation therewith a worm gear 34 which is adapted to mesh with the gear teeth 9 in the arm 7 when the carriage is in its forward position.

Also mounted on the shaft 30 is a cylindrical member 35; the bearing 33 and cylindrical member 35 carry suitable calibrations as indicated at 36 indicating minutes.

It will be seen that the cylindrical member 35 is attached to the knurled knob 31 by means of a pin 37 so that the two operate together and rotate the shaft 30 and worm gear 34.

From the foregoing it will be obvious that when the carriage 22 is in its forward position, the worm gear 34 meshes with the gear teeth 9 and by suitable operation of the knurled knob 31, the arm 7 is moved so as to swing the angle plate 2 about the pivot 5. Consequently, the adjustment in degrees and minutes may be obtained by first moving the carriage 22 rearwardly so as to disengage the worm gear 34, after which the thumb nuts 12 may be loosened and the plate 2 swung to the approximate degree desired as indicated on the graduations on the arm 7 in conjunction with the pointer 38 carried by the bracket 13.

The handle 29 is then swung to permit the cam 27 to allow the carriage 22 to move forwardly under the action of the spring 24, whereupon the gear 34 meshes with the teeth 9 and by suitable operation of the knurled knob 31, the adjustment in minutes can be obtained as shown by the calibrations carried on the cylindrical member 36 and bearings 33.

Referring to Fig. 5, it will be seen that the knurled knob 31 is formed integral with a toothed rack wheel 39 and as shown in Fig. 3, a pawl 40 is pivoted to a swinging arm 42 and is spring-biased by means of the spring 41 so as to throw the pawl into engagement with the teeth on the wheel 39 so as to prevent movement of the wheel and consequently of the shaft 30 in one direction. By this construction, it will be apparent that the angle plate 2 may be moved in one direction only upon operation of the minute adjusting knob 31, this movement being in a direction to cause the arm 7 to swing from zero to the proper location.

The mechanism for adjusting in seconds is carried by the carriage and consists of the arm 42 journaled for rotation about a hub 43 on the cylindrical member 35, this arm 42 being free to rotate independently of the cylindrical member 35 in one direction.

The arm 42 carries in its free end an aperture 44 and is spring-biased in one direction by a leaf spring 45 for a purpose to be hereinafter described.

The carriage 22 is provided with a bore 46 intersected by a slot 47 in which the free end of the arm 42 moves, the aperture 44 in the free end of the arm being located in the bore and the spring 45 normally biases the arm to move the aperture out of registration with the bore 46.

Mounted in the bore 46 is a sleeve 48 internally threaded to receive a threaded stem 49 having on operating knob 50 at one end and a conical point 51 at its opposite end.

The sleeve 48 and the knob 50 carry suitable graduations indicating seconds so that by operation of the knob 50, the angle plate 2 may be swung to obtain extremely fine and accurate adjustments.

This operation takes place as follows:

As indicated above, the arm 42 is normally swung by means of the spring 45 so that the aperture 44 is out of register with the bore 46. However, the conical end 51 is movable by the knob 50 so that the walls of the conical end bear against the walls of the aperture and swing the arm 42 towards the position where the aperture 44 and bore 46 will register. In view of the fact that the arm 42 carries the pawl 40 which is in engagement with the toothed wheel 39, it will be apparent from Fig. 3 that as the arm 42 swings so as to cause registry between the aperture 44 and the bore 46, rotary movement is imparted to the toothed wheel 39 and consequently to the shaft 30, worm gear 34, and the arm 7.

From the foregoing, it will be seen that three separate adjustments are possible by the present construction, the first being provided to approximate the angle in degrees by moving the carriage 22 rearwardly to disengage the worm gear from the rack teeth 9 whereupon the plate 2 may be swung to the approximate angle. The cam 27 is then operated to permit the worm gear 34 to engage with the teeth 9, whereupon operation of the knurled knob 31 in one direction will cause further movement of the plate 2 in accordance with the graduations in minutes, but being prevented from rotation in the opposite direction by means of the pawl 40 carried on the arm 42. Further adjustment of the angle plate 2 is accomplished by turning the seconds adjusting knob 50, whereupon the conical end 51 rides up or down in the aperture carried in the end of the arm 44, positively swinging the arm 42 in one direction and, through the pawl 40, rotative movement is imparted to the toothed wheel 39 and eventually to the angle plate 2; the retrograde movement of the arm 42 taking place under the influence of the spring 45 so that the aperture 44 and bore 46 are out of registry and the side of the conical end 51 bears against the wall of the aperture 44 in position to swing the arm 42 in a clockwise direction (Fig. 3) upon movement of the seconds adjusting knob 50.

I claim:

1. The combination with a base carrying a pivotally mounted plate thereon; said plate being provided with an arcuate toothed arm carrying calibrations in degrees and having means to hold the plate at the approximate position of adjustment, of a bracket carried by said base having a slide way thereon; a carriage slidably in said way and carrying a worm wheel meshing with the teeth on said arm; a shaft carrying said worm wheel and a toothed rack wheel and having calibrations in minutes associated therewith, means for rotating said shaft to adjust the said plate, and means for adjusting said plate by seconds also carried by said carriage, said last named means comprising

ing an apertured arm carried by the worm wheel shaft and freely rotatable thereabout in one direction, a pawl carried by the apertured arm and engaging said tooth rack wheel to impart movement to said worm wheel when the apertured arm is moved in the opposite direction, and a stem having a conical end projecting into the aperture and engaging the wall thereof, said stem being movable to swing said apertured arm and having calibration in seconds associated therewith.

2. A device for adjusting an angularly adjustable member carrying a rack portion comprising a bracket, minute and seconds adjusting mechanism for said member carried by said bracket; said mechanism comprising a worm wheel adapted to engage said rack portion, a rotary worm shaft secured to said worm wheel and having calibrations in minutes associated therewith, an apertured arm freely rotatable about said shaft in one direction, means for locking the arm and shaft for rotation together when moved in the opposite direction, and a stem having a conical end movable in said aperture to swing the arm and rotate said worm wheel.

3. A device for adjusting an angularly adjustable member carrying a rack portion comprising a bracket, minute and seconds adjusting mechanism for said member carried by said bracket, said mechanism comprising a worm wheel adapted to engage said rack portion, a rotary worm shaft secured to said worm wheel and having calibrations in minutes associated therewith, an apertured arm freely rotatable about said shaft in one direction, means for locking the arm and shaft for rotation together when moved in the opposite direction and a stem having a conical end movable in said aperture to swing the arm and rotate said worm wheel, and means for biasing said apertured arm to cause engagement between the said conical end and the walls of said aperture.
